United States Patent Office

Des. 183,387
Patented Aug. 19, 1958

183,387

TROPHY BASE

Alfred John Flauder, Trumbull, Conn.

Application October 16, 1957, Serial No. 48,130

Term of patent 7 years

(Cl. D29—23)

Fig. 1.

Fig. 2.

Fig. 3.

Fig. 4.

Fig. 5.

Fig. 1 is a front elevational view of a trophy base, showing my new design;

Fig. 2 is a side elevational view;

Fig. 3 is a top plan view of the same;

Fig. 4 is a horizontal sectional view taken on the line 4—4 of Fig. 1; and

Fig. 5 is a horizontal sectional view taken on the line 5—5 of Fig. 1. *

I claim:

The ornamental design for a trophy base, substantially as shown.
